US00D849037S

(12) **United States Design Patent** (10) **Patent No.:** **US D849,037 S**
Li et al. (45) **Date of Patent:** **** May 21, 2019**

(54) **MOBILE COMMUNICATION TERMINAL WITH GRAPHICAL USER INTERFACE**

(71) **Applicant:** **BEIJING KINGSOFT INTERNET SECURITY SOFTWARE CO., LTD.,**
 Beijing (CN)

(72) **Inventors:** **Yuan Li**, Beijing (CN); **Delin Liu**,
 Beijing (CN); **Zhe Ma**, Beijing (CN)

(73) **Assignee:** **Beijing Kingsoft Internet Security Software Co., Ltd.**, Beijing (CN)

(**) **Term:** **15 Years**

(21) **Appl. No.:** **29/635,333**

(22) **Filed:** **Jan. 30, 2018**

Related U.S. Application Data

(62) Division of application No. 29/586,814, filed on Dec. 7, 2016, now Pat. No. Des. 823,317.

(57) **CLAIM**

The ornamental design for a mobile communication terminal with graphical user interface, as shown and described.

DESCRIPTION

FIG. 1 is a front elevation view of a first embodiment of a mobile communication terminal with graphical user interface; and,

FIG. 2 is a front elevation view of a second embodiment of the mobile communication terminal with graphical user interface.

The broken lines shown in the drawings of a mobile communication terminal and certain graphic features of the graphical user interface form no part of the claimed design.

1 Claim, 2 Drawing Sheets
